DRAFT SWITCH

Arthur F. Geisel, Milwaukee, Wis., assignor to
 Perfex Corporation, Milwaukee, Wis., a corpora-
 tion of Wisconsin

Application June 5, 1946, Serial No. 674,543

4 Claims. (Cl. 200—83)

1

This invention relates generally to a switching mechanism for controlling an electric circuit and more particularly to a switching mechanism responsive to changes in condition, such as pressure or temperature, for controlling a condition regulator.

In the preferred embodiment of this invention, herein disclosed, the switching mechanism is adapted to respond to changes in the amount of draft air being supplied to a furnace for the burning of fuel. Upon a change in the amount of draft air supplied, the proper electrical circuit is completed to a damper operator which in turn moves a draft damper in a direction to bring the amount of draft air supplied back to the desired value.

An object of my invention is to provide a switch mechanism of the character described which has a structure of simple character and design and can be manufactured at a relatively low cost.

A further object of my invention is to provide a device of the character described which will successfully operate for a long period of time without frequent readjustments.

A further object of my invention is to provide a device of the character described which is capable of adjustment for operation within relatively close limits.

Other objects of this invention will appear from the following description and the appended claims.

For a full disclosure of the invention, reference is made to the accompanying drawings in which,

Fig. 1 represents a front view partly in section with the cover removed; and

Fig. 2 represents a side view, in section, with the cover removed.

The reference number 10 refers to a mounting base with upturned edges 11. Fastened to the mounting base are three mounting brackets 12, 13, and 14 with suitable mounting holes therein. Four tubular mounting spacers (two of which 15 and 16 are shown) are fastened to the mounting base 10 by means of bolts 17, 18, 19, and 20 which are turned into screw-threaded holes in the mounting base 10. A flanged dish member 21 and a similar dish member 22 form a diaphragm-chamber which is mounted on said four spacers. The bolts 17, 18, 19 and 20 pass through suitable holes in the flanges of the dished members. An inlet chamber is provided consisting of the dead-end tubular section 28, which passes through a cutaway portion of the upturned edge 11 and is fastened to the mounting base 10 by means of

2

the screws 29 and 30. The tubular section 28 is threaded at 31 to receive an inlet pipe. A tube 32 extends from tubular section 28 through an opening in the flanged dish member 22. An inlet passage is thus provided from the tubular section 28 through the inlet tube 32 into the diaphragm-chamber.

The diaphragm-chamber formed by the two dish members 21 and 22 contains a flexible diaphragm clamped between the two flanged, dish members 21 and 22 and the diaphragm mounting spacers 27. Two diaphragm stiffening members 33 and 34 are fastened to the diaphragm at 35, 36, and 37. The stiffening members 33 and 34 are provided with outwardly extending edges, and are beaded at 38 and 39 for additional rigidity. The diaphragm is thus so constructed that any flexing or bending of the diaphragm takes place at the flexible portions 38 and 39.

20 A mounting lug 41 is riveted to the stiffening member 33. A link member 43 is riveted to the mounting lug 41, and extends through an opening 44 in the front dish member 21.

A flanged supporting member 52 is secured to the front dish member 21 at 55, 56, 57, and 58. A U-shaped bracket 48, carrying the pivot pin 49 and spacers 50 and 51, is fastened to the supporting member 52 as shown in Fig. 1. A lever member 45 is pivoted near one of its ends on the pivot pin 49, and at its other end on the pivot pin 47 which is carried by the link member 43. A U-shaped switch supporting member 68 is fastened to the front dish member 21 at 69, 70, 71, and 72. A bracket 66 is mounted at 67 on the switch supporting member 68 and carries a spring hinge 64. An operating member 60 is fastened, at one of its ends, to the spring hinge 64. The operating member 60 has an in-turned portion 61, and a pivot pin 59 extending therefrom. The pivot pin 59 extends through an elongated opening 62 in lever member 45. An enlarged opening in the in-turned portion 61 of the operating member 60 allows the pivot pin 47 to extend loosely through this portion, as shown in Fig. 1.

45 Switch actuating arms 73 and 74 are mounted on the operating member 60, with a spacer 76 between the resilient member 64 and the actuating arm 74. Tapped holes in the switch actuating arms 73 and 74 receive the actuator members 77 and 78. Actuator members 77 and 78 are adapted to engage the thrust members 79 and 80 of the normally open, enclosed switches 81 and 82 respectively. The switches 81 and 82 are so designed that a small inward movement of the thrust members 79 and 80 will close their nor-

mally open contacts. These switches 81 and 82 form no part of the present invention. The switches 81 and 82 are fastened to the supporting member 68 by means of the bolts 101 and 102 which are screw-threaded into the spacing member 104. The actuator member 78 extends through an opening in the switch supporting member 68 and is fitted with a manual setting knob 83, an indicating pointer 84, and stops 85 and 86 (see Fig. 1). Rotating the manual setting knob 83 varies the amount of the movement of the actuating arm 74 necessary to close switch 82, thus providing a "differential" adjustment. It will be noted that actuator 77 is in threaded engagement with actuating arm 73 for proper "factory adjustment" of the amount of movement of the actuating arm 73 necessary to close switch 81.

One end of a tension spring 87 is fastened to the lever member 45, as at 88. The other end of the spring 87 is fastened to a spring holder 89. Threaded through the spring holder 89 is an adjusting screw 90 which extends through the supporting member 52. The adjusting screw 90 is provided with a slotted head 91, lock nuts 92 and 93, and compression spring 94. The spring holder 89 is prevented from turning upon rotation of the adjusting screw 90 by means of an extending portion 95. As may best be seen in Fig. 1, the outer end of the extending portion 95 is fitted into a longitudinal slot 96 in the supporting member 52. Rotation of the adjusting screw 90 results in changing the position of the spring holder 89 and consequently changing the tension in the spring 87. This provides "range" adjustment.

A bracket 97, fastened to the supporting member 52, has a threaded opening 98 to receive a cover mounting screw 99 (shown by broken lines in Fig. 2). The cover mounting screw 99 holds in place a cover 100 (shown by broken lines in Fig. 2).

In the form disclosed, the switch is adapted to react to variations in draft pressure. The portion of the diaphragm chamber to the left of the diaphragm (as viewed in Fig. 2) is at atmospheric pressure. The portion of the diaphragm chamber to the right of the diaphragm is at draft pressure which will be less than atmospheric pressure. The resulting force tending to move the diaphragm to the right is balanced by the tension spring 87, whose pull is adjusted by means of the adjusting screw 90 to a value equal to the difference between atmospheric pressure and the desired draft pressure. When spring 87 is so adjusted, the diaphragm and the operating member 60 are in their neutral position and neither switch 81 nor 82 is actuated to its closed position. Upon an increase in draft the pressure on the right of the diaphragm (as viewed in Fig. 2) decreases and the diaphragm is moved to the right. This motion is transmitted to the operating member 60 through the link member 43, lever member 45, and pin 59. The resulting slight clockwise rotation of the operating member 60 causes the actuating arm 73 and actuator member 77 to close the contacts of the normally open switch 81. With the diaphragm at its neutral point, that is, with the draft pressure plus the pull of the tension spring 87 just equal to atmospheric pressure, if the draft should decrease, the pressure in the diaphragm chamber to the right of the diaphragm will increase. The resulting movement of the diaphragm to the left (as viewed in Fig. 2) causes a slight counterclockwise rotation of the operating member 60. This movement of the op-

erating member 60 causes the actuating arm 74 and actuator member 78 to close the contacts of the normally open switch 82.

I have herein shown and described certain embodiments of my invention for the purpose of explaining its principles and showing its application. Numerous modifications may be made without departing from the principles of the invention which are included in the following claims.

What is claimed is:

1. In a condition responsive switch, an operating member with two switch actuating arms oppositely extending therefrom, resilient mounting means attached to said operating member, differential adjusting means attached to one of said switch actuating arms, switching means adjacent each of said switch actuating arms, one of said switching means adapted to be actuated by one of said switch actuating arms upon movement of said operating member in one direction, the other of said switching means adapted to be actuated by the other of said switch actuating arms upon movement of said operating member in another direction, condition responsive means, moving means for moving said operating member when said condition responsive means responds to a change in condition, and adjustable resisting means resisting movement of said operating member by said moving means.

2. In a pressure switch, an operating member with switch actuating arms extending therefrom, resilient mounting means attached to said operating member, differential adjusting means screw threaded into one of said switch actuating arms, differential adjustment indicating means associated with said differential adjusting means, said differential adjustment indicating means consisting of an indicating pointer rotated between stop members, switching means adjacent each of said switch actuating arms and adapted to be actuated by said switch actuating arms upon movement of said operating member, pressure responsive means, moving means for moving said operating member when said pressure responsive means responds to a change in pressure, and adjustable resisting means resisting movement of said operating member by said moving means.

3. In a condition responsive switch, an operating member with switch actuating arms extending therefrom, resilient mounting means attached to said operating member, differential adjusting means screw-threaded into one of said switch actuating arms, differential adjustment indicating means associated with said differential adjusting means, said differential adjustment indicating means consisting of an indicating pointer rotated between stop members, switching means adjacent each of said switch actuating arms and adapted to be actuated by said switch actuating arms upon movement of said operating member, condition responsive means, moving means for moving said operating member when said condition responsive means responds to a change in condition, and adjustable resisting means resisting movement of said operating member by said moving means.

4. In a condition responsive switch, an operating member with two switch actuating arms oppositely extending therefrom, resilient mounting means attached to said operating member, differential adjusting means attached to one of said switch actuating arms, switching means adjacent each of said switch actuating arms, one of said switching means adapted to be actuated by one

of said switch actuating arms upon movement of said operating member in one direction, the other of said switching means adapted to be actuated by the other of said switch actuating arms upon movement of said operating member in another direction, condition responsive means, moving means for moving said operating member when said condition responsive means responds to a change in condition, said moving means comprising a first member operatively secured to said condition responsive means, a second member having a stationary pivotal mounting, said second member having a movable pivotal connection with said first member, said operating member also having a movable pivotal connection with said second member, and adjustable resisting

means resisting movement of said operating member by said moving means.
